(57) **CLAIM**

The ornamental design for a sledge/mattock tool head, as shown and described.

DESCRIPTION

FIG. 1 is a perspective view of a sledge/mattock tool head.

FIG. 2 is a top view thereof;

FIG. 3 is a left side view thereof;

FIG. 4 is a front view thereof;

FIG. 5 is a right side view thereof;

FIG. 6 is a rear view thereof; and,

FIG. 7 is a bottom view thereof.

The broken line showing of the shaft is included for the purpose of illustrating environmental structure and forms no part of the claimed design.
